[57] CLAIM

The ornamental design for a bottle carrier, substantially
as shown.

DESCRIPTION

FIG. 1 is a top plan view of a bottle carrier, showing my
new design;

FIG. 2 is a bottom plan view thereof;

FIG. 3 is a front elevation view thereof, the rear elevation
being a mirror image thereof;

FIG. 4 is a right side elevation view thereof, the left side
elevation being a mirror image thereof; and

FIG. 5 is a top front perspective view thereof at a re-
duced scale.

FIG. 1

FIG. 3

FIG. 4
